STRAIGHT BEAM CLAMPING AND LIKE
MEANS WITH ADJUSTABLE AND IN-
TERCHANGEABLE PADS

Bernard William Dawkins, Southport, England

Application June 25, 1951, Serial No. 233,363
In Great Britain May 20, 1950

2 Claims. (Cl. 144—303)

1

This invention relates to clamps, presses and the like such as are used mainly by cabinet makers or joiners and also engineers, and has for its object to provide means of a universal nature capable of use either as a clamp or press for forcing wooden or other work members together or as a jack for forcing working members apart.

In the accompanying drawings:

Figure 1 is elevation of clamp according to this invention.

Figure 2 is a view of the right hand end of Figure 1.

Figures 3 and 4 are detail end and sectional views respectively.

Figure 5 is an elevation of part of the clamp shown assembled in an alternative form.

Figures 6 and 7 are elevations of cross heads or blocks carrying work engaging members having pivotal and universal adjustment respectively to adapt them for work engagement and

Figures 8 and 9 are plan views of the work engaging members per se as shown in elevation in Figures 6 and 7, respectively.

Throughout the drawings like parts are designated by the same reference numerals.

In carrying the present invention into practice, as shown in the accompanying drawing, the longitudinal members may consist of bars, rods or the like but preferably take the form of tubes 1 in order to give lightness to the structure without loss of rigidity or necessary strength.

Each cross head 2 may conveniently consist of a block having a series of parallel through holes 3 therein suitably spaced apart so that on each cross head 2 engaging a pair of longitudinal members or tubes 1 by two holes 3 therein a third hole 3 is left available to receive a clamping or work engaging member indicated generally at 4.

The cross heads 2 may be locked to the tubes 1 in any suitable manner by clamps or the like but in the preferred embodiment of the invention shown the cross heads 2 have smaller holes 5 one to each said parallel hole 3 the axis of the smaller hole 5 being in the same plane but at right angles to its associated larger hole 3 so that a peg 6 may be passed through each cross head 2 and through any one of a series of preferably equidistant transverse holes 7 in the tubes 1 in order to positively lock each cross head 2 to a tube or tubes 1.

The pegs may as shown, be provided with heads 8 and be either split at their leading ends as at 9 (Figure 3) for a friction fit through the cross heads 2 and tubes 1 or threaded at said end to receive a nut 10, Figure 2.

2

Each clamping or work engaging member 4 consists of a pad 11 or like member such as a disc having a surface suitable for engaging finished work of wood or other material, said pad 11 being adapted to have a spigotted engagement with a hole 3 and receiving a bolt serving as a threaded shank 12 thereto which extends from the rear of the pad for passage through a hole 3 of a cross head 2 to receive a nut 14 for securing the pad 11 in position on the cross head, which nut 14 also has a spigotted engagement with the hole 3 for accurate location therein.

In order to enable clamping pressure to be exerted, screw means 15 are provided consisting of an internally threaded bush 16 adapted to accurately fit a parallel hole 3 in a cross head 2 and be located therein by means of a head portion 17 at one end and a nut 18 screwing onto an externally threaded part at the other end 15 (Figure 4) or by means of two such nuts 18 at each end. The said bush 16 receives a threaded rod 19 of suitable length which latter carries a knurled or like head 20 keyed thereto to enable the rod 19 to be readily rotated for axial adjustment in the bush 16, which latter is held against rotation in the hole 3 by a key 30 engaging a recess 31 in the cross head 2 (Figure 4).

In employing the means according to this invention as a clamp three cross heads 2 (designated A, B and C in Figure 1), are slid onto a pair of tubes 1 the latter passing through adjacent parallel holes 3 of the cross heads A, B, C, i. e. through central holes 3 and corresponding outer holes.

35 One endmost cross head A is keyed to the tubes 1 by pegs 6 and carries by its third parallel hole 3 a clamping pad 11 whilst the next cross head B is left free to slide on the parallel tubes 1 and carries a further pad 11 opposed to the first mentioned pad. The third cross head C carries the pressure exerting screw means 15 and is adapted to be keyed by means of pegs 6 behind the slideable cross head B for applying final clamping pressure to the pad 11 of the latter.

40 In use, the slideable cross head B is slid along the tubes 1 for initially engaging the pads 11 with the work such as a wooden frame. The third cross head C is then keyed behind the slideable cross head B by selection of a suitable peg hole 7 in each tube 1 whereupon the threaded rod 19 is screwed to abut the end of the shank 12 of the pad 11 carried by the slideable cross head B, for applying clamping pressure thereto and hence to the work.

45 55 In the case of a press the disposition of the three cross heads A, B, C, is similar except that

the opposed clamping pads 11 and pressure exerting screw 15 are carried by central holes 3 in the cross heads 2 the tubes 1 occupying the outer holes 3 to form with the cross heads 3 a closed structure and Figure 5 shows the cross heads B and C arranged in this latter manner.

When used as a jack for forcing work members apart the disposition of the tubes 1 relative to the cross heads 2 may be as that described for a press or clamp, preferably the latter. However, the endmost cross heads carry the clamping pads 11, one being pegged and the other slideable whilst the cross head carrying the pressure exerting screw 15 is positioned between the said pad carrying cross heads for pegged location behind the slideable head of the latter.

The means according to this invention may also include a pivotally mounted adjustable pad 11 (Figures 6 and 8) for engaging work having opposite surfaces that are inclined. Such an adjustable pad 11 may comprise the threaded shank 12 to receive a nut 14 for fitting in a cross head hole 3 as before, said shank 12 also having a forked head 21 receiving a lug 22 on the back of the actual clamping pad 11, said lug being held in the forked head 21 by a transverse headed pin 23 receiving a nut 24, tightening of the latter holding the pad 11 in an adjusted position.

In a further development of the above shown in Figures 7 and 9 a universal adjustment of the pad 11 is obtained by mounting in the forked head 21 of the shank 12, a lug 25 of a further forked head 26 which, in turn, receives the lug 22 on the back of the pad 11, which latter lug is held in the forked head 26 by a headed pin 27 receiving a nut 28, the pins 23, 27 providing axes at right angles to one another for obtaining universal adjustment of the pad 11.

The operative surfaces of the pads 11 may be faced with suitable material such as rubber to avoid damage to the work and the cross heads 2 may also have lightening holes 29 therein.

I claim:

1. Clamping and like means comprising in combination three cross heads each having at least three identical parallel holes therein, together with peg holes transverse to each said parallel hole; at least two longitudinal members interchangeably engaging two of said parallel holes in each cross head, said longitudinal members having spaced transverse peg holes therein adapted to register with the peg holes in said cross heads; pegs passing through peg holes in two of said cross heads and the two longitudinal members for selectively locking said two cross heads along the longitudinal members whilst the

third cross head is left slideable thereon; two work engaging members having shank like parts interchangeably engaging other of said parallel holes in one of said pegged cross heads and said slideable cross head; and pressure exerting screw means interchangeably carried by a said parallel hole in the other pegged cross head for acting upon the slideable cross head carrying a work engaging member to move the latter cross head along said longitudinal members, the arrangement of said parallel holes in the cross heads permitting alternative interchangeable arrangements of said longitudinal members, work engaging members and pressure exerting screw means in engagement with said cross heads for forming a clamp, press, jack or the like as required.

2. Clamping and like means comprising in combination three cross heads each having at least three identical parallel holes therein; at least two longitudinal members interchangeably engaging two of said parallel holes in each cross head; locking means for selectively locking two of said cross heads along the longitudinal members whilst the third cross head is left slideable thereon; two work engaging members having shank like parts interchangeably engaging other of said parallel holes in one of said locked cross heads and said slideable cross head; and pressure exerting screw means interchangeably carried by a said parallel hole in the other locked cross head for acting upon the slideable cross head carrying a work engaging member to move the latter cross head along said longitudinal members, the arrangement of said parallel holes in the cross heads permitting alternative interchangeable arrangements of said longitudinal members, work engaging members and pressure exerting screw means in engagement with said cross heads for forming a clamp, press, jack or the like as required.

BERNARD WILLIAM DAWKINS.
